UNITED STATES PATENT OFFICE.

DOMINICK O'DONNELL, OF NEW YORK, N. Y.

ADJUSTMENT DEVICE.

1,107,699.

Specification of Letters Patent. Patented Aug. 18, 1914.

Application filed May 2, 1913. Serial No. 765,018.

To all whom it may concern:

Be it known that I, DOMINICK O'DONNELL, a citizen of the United States, and a resident of the city of New York, borough of Manhattan, in the county and State of New York, have invented a new and Improved Adjustment Device, of which the following is a full, clear, and exact description.

The invention relates to men's trousers, 10 drawers and like garments, and its object is to provide a new and improved adjustment device for use on the waistband of the garment and arranged to allow convenient adjustment of the waistband to properly fit 15 the waist of the wearer.

In order to accomplish the desired result use is made of a tape or band extending lengthwise of the waistband and secured at one end to the waistband, the other end of 20 the tape having a doubled-up portion forming a loop engaging an eye attached to the waistband a distance from the fixed end of the tape, and a slide made of a single piece of sheet metal fashioned to form a 25 rectangular frame provided with spaced cross bars intermediate the end bars of the frame and spaced therefrom to provide end openings, the said cross bars being spaced apart to form a middle opening between 30 the same, and one of the cross bars forming an attaching bar for the terminal of the doubled-up portion of the tape, the latter passing through the said end openings and overlying the said cross bars at the front 35 thereof, the said clamping cross bar ranging toward the fixed end of the tape and being provided with a clamping member extending from the inner edge of the said clamping cross bar and bent over onto the back there- 40 of toward the fixed end of the tape, the doubled-up portion of the tape passing through the middle opening from the back of the slide and extending over the front of the said clamping cross bar and through 45 the end opening adjacent thereto, the terminal of the doubled-up portion being clamped to the back of the clamping cross bar by the said clamping member.

A practical embodiment of the invention 50 is represented in the accompanying drawings forming a part of this specification, in which similar characters of reference indicate corresponding parts in all the views.

Figure 1 is a side elevation of the ad- 55 justment device as applied to the waistband of a garment; Fig. 2 is an enlarged sectional

plan view of the same on the line 2—2 of Fig. 1; Fig. 3 is an enlarged sectional plan view of the same, on the line 3—3 of Fig. 1; Fig. 4 is a face view of the blank from which 60 the slide is formed; and Fig. 5 is a rear perspective view of the slide.

The adjustment device illustrated in the drawings, is shown applied to the waistband A of a man's trousers, drawers or 65 similar garment B, and the adjustment device consists essentially of a tape or a band C and a slide G for lengthening or shortening the tape C, as hereinafter more fully explained. One end of the tape C is sewed 70 or otherwise secured at D to the waist band A, and the other end of the tape has a doubled-up portion C' forming a loop engaging an eye E sewed or otherwise fastened at F to the waistband A a distance 75 from the fixed end D of the tape C somewhat less than the length of the tape C. The tape C is lengthened or shortened by the use of a slide G, preferably made of a single piece of sheet metal fashioned to 80 form an approximately rectangular frame, having end bars G', G² and top and bottom bars G³, G⁴. The top and bottom bars G³, G⁴ are connected with each other intermediate the end bars G', G² by cross bars G⁵, G⁶ 85 spaced from the end bars G', G² to form end openings H, H', and the said cross bars G⁵, G⁶ are spaced apart to form a middle or a central opening H². In making the slide, the material at the middle of the blank is 90 struck up to form the opening H² and to provide a clamping member G⁷ which extends integrally from the inner edge of the cross bar G⁶ and is bent over onto the back of the said cross bar G⁶ to form with the 95 latter a clamping device for securing the terminal of the doubled-up portion C' in position between the bars G⁶, G⁷.

In manufacturing the adjustment device, the tape C is passed through the end open- 100 ings H, H' from the rear of the slide so that the tape overlies the cross bars G⁵, G⁶ at the front of the slide, as will be readily understood by reference to Figs. 1, 2 and 3. The doubled-up portion C' after being 105 passed through the eye E is passed through the middle opening H² from the back of the slide and then is passed over the front of the clamping cross bar G⁶ to have its terminal clamped between the said bar G⁶ 110 and the clamping member G⁷ (see Fig. 3). It will be noticed that by fastening the end

of the doubled-up portion C' around the clamping cross bar G⁶ in the manner described the strain on the tape is taken up by the clamping cross bar G⁶ and the member G⁷ is not liable to tear out or become loose. It will further be noticed that by arranging the slide G on the tape C in the manner described the slide can be readily moved lengthwise of the tape to the right or to the left, it being understood that when the slide G is moved to the right the tape is shortened to reduce the size of the waistband, and when the slide G is moved to the left the tape is lengthened to let out the waistband to fit a larger sized waist.

The adjustment device shown and described is very simple in construction, and can be cheaply manufactured and readily applied to waistbands and the like requiring adjustment relative to size so as to properly fit the wearer.

Having thus described my invention, I claim as new and desire to secure by Letters Patent:

In combination, a waistband, a tape extending lengthwise of the said waistband and secured at one end to the waistband, the other end of the tape having a doubled-up portion forming a loop, an eye attached to the waistband a distance from the fixed end

of the tape, the said distance being less than the length of the tape, and a slide made of a single piece of metal fashioned to form a rectangular frame provided with two spaced cross bars intermediate the end bars of the frame and spaced therefrom to form end openings with the said end bars, the said cross bars being spaced apart to form a middle opening between the same and one of the cross bars forming an attaching bar for the terminal of the doubled-up portion of the tape, the latter passing through the said end openings and overlying the said cross bars at the front thereof, the said attaching cross bar being toward the fixed end of the tape, the doubled-up portion of the tape passing through the middle opening from the back of the slide and extending over the front of the said attaching cross bar between said bar and the tape and through the end opening adjacent thereto, the terminal of the doubled-up portion being secured to the back of the said cross bar.

In testimony whereof I have signed my name to this specification in the presence of two subscribing witnesses.

DOMINICK O'DONNELL.
